RHEOSTAT

George L. McFarland, Jr., Scotia, N. Y., assignor
to General Electric Company, a corporation of
New York

Application January 28, 1942, Serial No. 428,567

6 Claims. (Cl. 201—55)

My invention relates to rheostats, more particularly variable or adjustable rheostats, such as used in the control of electrical apparatus, and has for its object a simple, low cost and rugged rheostat and, furthermore, a rheostat made up of a plurality of electric resistors which are replaceable in case of damage and whose electric resistance may be graduated as desired.

In carrying out my invention in one form, I utilize as resistors or resistance units a plurality of relatively short resistance heating units of the sealed metal encased type which I arrange radially and clamp together by means of plates provided with apertures for ventilating the inner ends of the resistance units. I also provide an insulating support in the center of these radially arranged units on which are a plurality of contacts connected to the terminals of the units and a contact arm engaging these contacts by means of which the amount of the resistance in the electric circuit can be varied.

For a more complete understanding of my invention, reference should be had to the accompanying drawing in which Fig. 1 is a plan view of a dial type rheostat embodying my invention; Fig. 2 is a view mainly in vertical section of the device shown in Fig. 1; while Figs. 3 and 4 are fragmentary views showing details of construction.

Referring to the drawing, in one form of my invention I provide a plurality of resistance units or resistors 10 consisting of metal encased heating units. Seventeen of these resistors 10 are shown arranged radially so as to leave a circular opening in the center of these radially arranged resistors. In this central opening is a support 11 made of a suitable electrically insulating material such as a heat resisting compound, this support being circular in shape and somewhat smaller than the central opening defined by the resistors so as to be spaced from the inner ends of the resistors.

On the periphery of the support 11 arranged in equally spaced relation with each other are a plurality of electric contacts 12 having their upper surfaces, as seen in Fig. 2, substantially flush with each other and lying in a plane surface thereby to be engaged by a brush 13 on the end of a contact arm 14 secured to an operating knob or handle 15. This handle is mounted on a pivot pin 16 pivotally mounted centrally on the support 11 so that by turning the handle the contact brush 13 is moved over the contacts 12.

The terminal leads 17 from each of the resistors 10 are suitably connected electrically to the

contacts 12. As shown, each resistor has four terminals 17 extending from its inner end, which terminals are connected to four contacts with the adjacent terminals of two adjacent resistors connected to the same contact whereby the whole series of seventeen resistors is connected in a closed electric circuit. At one side, as shown, the lower side, a substantial space is left between the two adjacent resistors into which extends a projection 11a on the insulating support 11. The two end contacts 12 are connected by conductors 18 and 19 to electric terminals 20 and 21 on this extension 11a. Also, a third terminal 22 is connected by conductor 23 to the contact arm 14. This latter connection is preferably effected by connecting the conductor 23 to a circular plate 24 secured so as to establish a circuit between the plate 24 and the contact 12 on which the brush 13 bears.

10 The plurality of resistors and the support 11 are clamped firmly together in the relation shown by means of upper and lower metallic clamping and supporting plates 26 and 27. These plates are circular in form and of the same circular size, and each has a series of radial indentations 28 extending respectively downward and upward between the pairs of resistors. Also, the indentations 28 and 29 are slightly wider at their outer ends so as to fit closely between the pairs of resistors. These plates are clamped together by a series of bolts 30 extending through the indentations 28 and 29 between each pair of resistors, the two plates having their centers coincident with the center line of the pin 16.

15 At its center, the lower plate 27 is bent upward somewhat to form a raised support 31 for the insulating support 11 which is secured thereto by bolts 32. As shown, the support 11 is raised far enough so that its lower edge is slightly above the resistor terminals 17, as seen in Fig. 2, so that terminals can be easily secured to the bottoms of the contacts 12. As shown in Fig. 2, each contact preferably is a strip of metal arranged radially with respect to the pin 16 and having end portions extending downward through the support and bent over toward each other on the bottom of the support. A series of notches around the periphery of the support 11 is provided for the outer lengths of the contacts 12.

20 The center of the upper plate 26 is raised somewhat to form a cover portion 33 over the contact arm 14, the cover being provided with an aperture 34 through which the knob 15 extends, this aperture being considerably larger than the knob to provide ventilation. Additional ventilating

55

apertures 35 are provided around the side supporting wall of the raised portion 33. Likewise, the ventilating apertures 36 are provided in the supporting wall of the bottom support 31.

The resistors 10 are the type of heating unit in which the resistance conductor 37 is embedded in refractory insulating material 38, such as magnesium oxide, which is suitably compacted as by reducing the cross section of the metal sheath 31a containing the insulating material. The heating unit may be somewhat similar in construction to that described and claimed in United States Patent No. 1,904,594, issued to Charles C. Abbott on April 18, 1933. Although I have shown four terminals 17 coming out of the end of each heating unit and extending through a suitable insulator 39 at the end of the sheath, any suitable number can be used. As shown, the resistance conductor 37 is passed back and forth in a plurality of zigzag lengths from one end of the heating unit to the other, the ends of the resistance conductor being connected to the two outside terminals and each loop being connected electrically to an inside terminal.

In use, the entire resistance may be connected in the electric circuit by electrical connections to the terminals 20 and 21. The central terminal 22 will be electrically connected to one of the outside terminals so that the resistance between this outside terminal and the arm 14 is short-circuited. Thus by turning the knob 15, a desired amount of the resistance can be cut in or out thereby to vary the amount included in the electric circuit.

Moreover, by using resistor units each having different electrical resistances and by suitably arranging them, any desired graduation of resistance or resistance gradient can be obtained. Another advantage is that any resistor unit which may become damaged can be readily replaced without replacement of the entire rheostat.

Moreover, the rheostat is adapted to withstand shocks and vibrations without damage. This is particularly true because of the mounting of the resistance conductor 37 in compacted insulating material 38 so that it is held securely against movement. Also, this rheostat can be operated at high temperatures because the resistance conductors are sealed from contact with the air in the insulating material, and as a result a larger current can be passed through the resistance conductor for a given temperature rise.

Furthermore, this rheostat is especially adapted for high heat dissipation qualities by reason of the freedom of air movement over large surfaces of the resistor. Thus the outer ends of the radially extending resistors 10 are spaced apart so that cooling air can circulate freely around the exposed outer ends projecting from between the clamping plates 28 and 29. Furthermore the clamping plates, as shown in Fig. 4, are spaced apart at points between the resistors to provide a duct for the circulation of cooling air radially between the resistors.

Also, the apertures 35 and 36 provide for the free circulation of air through the center of the rheostat when the rheostat is mounted in a horizontal position. Moreover, with the rheostat in a horizontal position, an effective radial circulation of cooling air between the resistors will be set up. When the rheostat is mounted in a vertical position, the circulation of air through the central portion may not be as vigorous as compared with the horizontal position, but on the other hand, the circulation of air radially between the resistors will be more pronounced with

the rheostat in the vertical position except possibly for those resistors which are in nearly a horizontal position.

The two clamping plates 28 and 29, of course, 5 are in intimate thermal relation with the resistors by reason of the fact that they are clamped on the resistors. The plates, therefore, receive heat freely by conduction directly from the resistors and dissipate this heat to the air circulating around the rheostat.

While I have shown a particular embodiment of my invention, it will be understood, of course, that I do not wish to be limited thereto, since many modifications may be made and I therefore 15 contemplate by the appended claims to cover any such modifications as fall within the true spirit and scope of my invention.

What I claim as new and desire to secure by Letters Patent of the United States is:

20 1. A rheostat comprising a plurality of metal sheathed electric resistance units, upper and lower metal clamping plates between which said resistance units are mounted in positions to extend radially with respect to a common center, means 25 securing said plates together thereby to clamp said resistance units between said plates in good heat conducting relation with said plates, said resistance units being arranged to provide a space at their inner ends, and selective means in 30 said space secured to one of said plates, for varying the number of said units connected in an electric circuit.

2. A rheostat comprising a plurality of electric resistance units, upper and lower plates between 35 which said resistance units are secured in positions to extend radially with respect to a common center, means extending between said resistance units for pulling said plates together thereby to clamp said resistance units between 40 said plates in good heat conducting relation with said plates, said resistance units being arranged to provide a central space at their inner ends, and selective means in said central space mounted on one of said plates for varying the 45 number of said units in an electric circuit, said plates being spaced apart between said resistance units and being provided with apertures communicating with said central space thereby to provide for the circulation of cooling air through said central space and from said central space 50 radially outward between said plates and said resistance units.

3. A rheostat comprising a plurality of elongated electric resistance units each provided with 55 a plurality of electric terminals extending from one end, upper and lower metal clamping plates between which said resistance units are clamped in positions to extend radially with respect to a predetermined center, said resistance units being arranged to provide a space at their inner ends and with said terminal ends constituting said inner ends, a central raised portion on said lower clamping plate extending into said space, a support of electrically insulating material mounted 60 on said raised portion, a plurality of electric contacts secured to said insulating support, a contact arm mounted on said insulating support and moving over said contacts, electric connections between said terminals of said resistance units 65 and said contacts whereby said resistance units are connected together in series with each other, and a central raised portion on said upper clamping plate enclosing said contact arm.

4. A rheostat comprising a plurality of elongated electric resistance units each provided with

a plurality of electric terminals extending from one end, each of said resistance units being provided with a metallic sheath and with a resistance conductor embedded in electrically insulating material in said sheath, upper and lower metal clamping plates between which the metallic sheaths of said resistance units are mounted thereby to hold said resistance units spaced apart and in positions to extend radially with respect to a predetermined center, means extending between said units for pulling said plates together thereby to clamp said resistance units tightly between said plates in good heat conducting relation with said plates, said resistance units being arranged to provide a space at their inner ends and with said terminal ends constituting said inner ends, and selective means mounted on one of said clamping plates in said space, for varying the number of said units connected in an electric circuit.

5. A rheostat comprising a plurality of elongated electric resistance units each provided with a plurality of electric terminals extending from one end, each of said resistance units being provided with a metallic sheath and with a resistance conductor embedded in electrically insulating material in said sheath, upper and lower circular metal clamping plates between which the metallic sheaths of said resistance units are clamped thereby to hold said resistance units in positions to extend radially with respect to the center of said plates, a circular support of electrically insulating material mounted on said lower clamping plate, a plurality of electric contacts secured to the periphery of said insulating support, a contact arm pivotally secured to said

insulating support and moving over said contacts, electric connections between said terminals of said resistance units and said contacts whereby said resistance units are connected together in series with each other, and ventilating apertures in the central portions of said plates.

6. A rheostat comprising a plurality of elongated electric resistance units each provided with a plurality of electric terminals extending from one end, each of said resistance units being provided with a metallic sheath and with a resistance conductor embedded in electrically insulating material in said sheath, upper and lower circular metal clamping plates between which the metallic sheaths of said resistance units are clamped thereby to hold said resistance units in positions to extend radially with respect to the center of said plates, said resistance units being arranged to provide a circular space at their inner ends and with said terminal ends constituting said inner ends, a central raised portion on said lower clamping plate, a circular support of electrically insulating material mounted on said raised portion, a plurality of electric contacts secured to the periphery of said insulating support, a contact arm pivotally secured to the center of said insulating support and having a contact brush moving over said contacts, electric connections between said terminals of said resistance units and said contacts whereby said resistance units are connected together in series with each other, a central raised portion on said upper clamping plate enclosing said contact arm, and ventilating apertures in the peripheral supporting walls of said raised portions.
